UNITED STATES PATENT OFFICE.

JOHN W. NASMITH, OF MANCHESTER, ENGLAND.

APPARATUS FOR FOLDING OF CARTON BLANKS.

Application filed April 21, 1924. Serial No. 707,990.

To all whom it may concern:

Be it known that I, JOHN WILLIAM NASMITH, a subject of the King of Great Britain, and a resident of Heaton Mersey, 5 Manchester, in the county of Lancaster, England, have invented new and useful Improvements in Apparatus for Folding of Carton Blanks, of which the following is a specification.

10 In apparatus as commonly used for the folding of carton blanks after the necessary creasing has been effected, the blanks are fed lengthwise into the folding machine and the flaps to be folded over are raised by inclined faces in their traverse through the machine. 15 This of necessity calls for a very long machine, occupying much space. The object of the present invention is an apparatus to fold the flaps of the carton blanks over and 20 on to the body or centre of the blank without the necessity of providing the long and space-occupying inclined faces just referred to, and to simplify the folding apparatus generally.

25 With the above objects in view my apparatus consists of means for feeding the creased blanks into the folding apparatus and traversing them therethrough in a direction at right angles to the creases on 30 which they have to be folded, the foremost flap being automatically raised and folded over on the blank centre by retaining means during the traverse of the blank, and positive means for folding over the rear flap 35 which means operate in the direction of traverse of the blank.

Where a small gluing flap is provided on the edge of one of the flaps, that flap is the foremost in traversing the apparatus and it 40 is glued by holding it momentarily in contact with a gluing roller and lifting it from said roller before the traverse of the blanks brings the foremost foldable flap thereto, this lifting being automatically effected by 45 the edges of the foremost foldable flap coming upon the means which raise them as the first step in the operation of the folding thereof.

The apparatus will now be fully described with reference to the accompanying drawings, wherein:

Figure 1 is a plan of a carton blank creased ready for folding, a small gluing flap being shown attached to that foldable flap which is the first to be folded in passing through the apparatus;

Figure 2 is a side view of the carton blank after the gluing flap has been glued and the foremost foldable flap folded over;

Figure 3 is a similar view of the blank 60 when the apparatus has completed the folding;

Figure 4 is a view of the apparatus taken on a longitudinal section line and showing one of each set of a plurality of units which 65 effect the folding, rollers being shown in section where they extend across the apparatus;

Figure 5 is a plan of the apparatus employed for arresting the edge of a gluing 70 flap whilst glue is applied thereto; and

Figures 6 and 7 are details.

The drawings are not to any special scale.

Referring to the figures, the cartons, ready 75 cut and scored, are piled in a hopper of the usual kind and delivered one by one to the machine in the usual manner. The feed rollers 1, 2, and 1' and 2' pass the cartons forward. The glue tank T is of the usual kind and revolving therein is the glue roller 80 R working in conjunction with the squeezing roller S and operating as described in my British specification No. 8263 of 1911, so that a thin but regulatable film of glue is carried round by the roller S. The tank and rollers can be removed when the machine is 85 required to fold without gluing.

Between the feed rollers 1', 2', and the roller S is a rod 3 carrying arms 4 adjustable lengthwise on the rod and to which are 90 riveted a pair of blades 5 inclined as shown at 6. These blades are seen in plan in Figure 5 and one of them in perspective in Figure 6. The horizontal part 5 is longer than the inclined part 6 and they are made in 95 pairs. They are adjusted on the rod so that the body A B C of the carton to be operated on will pass between the inner edges of the inclined part 6, over which only the end parts F of the cartons pass.

Above the blades 5 is a rod 7 free to rock in its bearings. It carries fingers 8 adjusted longitudinally thereon and positioned so as to fall between the inclined parts 6 of the blades as shown in plan in Figure 5. Means, 105 such as the screw V, Figure 7, are provided to limit the rocking of the rod 7, so that the fingers 8 fall very close to the roller S without actually touching it. On the end of the rod 7 is a lever L, Figure 7, on which is the 110 adjustable weight W, so that the resistance of the fingers 8 to displacement by the on-

ward moving carton can be nicely regulated and their return to normal position assured when the carton has passed.

- The function of these organs is as follows.
- 5 The feed roller 1' is placed slightly forward of the centre of the roller 2' so as to direct the front edge of the carton downwards as it issues from the rollers. It passes over the horizontal part of the blade 5 and the front edge under the fingers 8, which compel the underside of the lip A to touch the roller S when this is in use. But only for an instant, because the end flaps F of the carton, riding up the inclined part 6 of the blades, 10 raise it and cause it also to push the fingers 8 away as they offer but slight resistance. When no gluing is required and the size of the carton permits they may be thrown over 15 out of the way by turning the lever L over.
- 20 The swinging levers 9 Figure 4, are adjustable longitudinally on the free shaft 10 and are each formed with a short arm 11 resting normally against the cross bar 12 adjustable vertically in the slots 13 by the 25 screw 14. The proximity of the lower end of the levers 9 to the blades 6 can thus be regulated. They are positioned on their shaft as shown in plan Figure 5, and receive the flaps F of the carton as it passes off the 30 inclined blades 6, giving way before it but offering some resistance by reason of the spring 32 attached to a lever 28 fixed on the end of the shaft 10. Their function is to 35 turn over the forward end B of the carton at the crease E as soon as this has passed under the fingers 8 or is free from the rollers 1', 2', when the fingers are not in use. If the lip A has been glued, the glue is now uppermost. As soon as the fold has 40 been made the doubled front edge of the carton (Figure 2) is presented naturally over the fixed plate 15 to the grip of the transporting rollers 16, 17. It will be understood that 17 and also 18 are not continuous 45 rollers but bosses acting only on the end flaps F of the cartons and adjustable lengthwise on their respective shafts M and X, to suit different widths of cartons. The rollers 18, 19 carry the carton forward over 50 the plate 20 so that the folded edge Figure 2 enters the recess 21 in the lower ends of the pendent levers 22. There are a number of such levers fixed at regular intervals 55 along the shaft 23, which is quite free to rock in its bearings 26. The lower lip of the recess 21 projects into grooves O formed in the curved front of the transverse grid casting 27 which reaches right across the machine resting on slides 31 formed on the 60 framing. It can be moved nearer to or further from the rollers 18, 19 as required and clamped in position. One or more of the levers 22 is provided with a projection 65 contacting with the set screw 25 in the cross bar connecting the bearings 26. These

are adjustable along the framing of the machine and are connected to the grid casting 27 by the rods 33, so that the pendent levers 22 can be adjusted along with the grid as desired, in relation to the rollers 18, 19, in 70 addition to a similar but more limited adjustment by the screws 25. The advancing carton pushes the levers 22 away as it is forced up the curved face of the grid 27, until the last crease D has passed over the 75 face of the plate 20 and as soon as the flap C is free from the rollers 18, 19, it turns up to the position of the dotted line N, being lifted by the teeth of flutes of the bosses 18. The carton then collapses and the rear 80 doubled edge passes down between the face 29 of the plate 20 and the nose of the grid 27 as indicated by the arrow to the grip of the press roller 30, which, under spring pressure, squeezes the flap C against the lip A and, if A is glued, causes it to adhere thereto. The bosses 18 may be made either with square or angular faces, flutes or teeth, or the teeth may be resilient, giving way and sinking into the body of the boss when contacting with the lower roller 19. Their 85 function is to raise the rear end of the carton and bend it at the crease D so that it will collapse under the weight of the levers 22 and pass down to the press rollers, when it 90 passes to a counting and stacking device of the ordinary kind.

I claim:—

1. Apparatus for folding carton blanks, comprising feed rollers, traversing rollers for the carton blank, inclined blades upon which the foremost flap of the carton blank ascends, yielding levers to check momentarily the foremost edge of said flap to turn it over upon the blank centre, toothed or like 100 wheels under which the blank with its foremost flap folded may pass, and yieldable levers to check the folded edge momentarily to allow the toothed or like wheels to raise the outer edge of the rear flap, in the direction of traverse of the blank, and on their return movement to discharge the now collapsed carton blank to press rollers in a delivery chute.

2. In combination with the features 115 claimed in claim 1 a gluing roller, and yieldable and adjustable fingers to arrest momentarily the edge of a gluing flap in contact with the said roller before the carton blank edge is raised by the inclined blades, substantially as hereinbefore set forth.

3. In apparatus having the features 120 claimed in claim 1, inclined blades upon which the edges of the carton blank ascends, pivoted levers yieldable against spring tension with the free end of which levers the ascending blank edge makes contact, and screw adjustable stops to limit the extent of angular movement of such levers, for the purpose hereinbefore set forth.

4. In apparatus having the features claimed in claim 1, rotating toothed or like wheels under which the carton blank passes after the foremost flap is folded, yieldable 5 pivoted levers against the free ends of which the blank abuts whilst the rotating toothed or like wheels raise the rear flap of the blank, and screw adjustable stop means for 10 limiting the extent of yielding angular movement of such levers, substantially as hereinbefore set forth.

5. In apparatus having the features claimed in claim 1, levers yieldable to the pressure of the traversing carton blank until the toothed wheels have raised the rear 15 flap thereof, and a chute to which the said levers deliver the blank on the return oscillation of such levers, substantially as hereinbefore set forth.

In testimony whereof I have hereunto set 20 my hand.

J. W. NASMITH.
